GAUGE BLOCK FINISHING

Raymond Gaerlich, Jordan, Minn., assignor to
 Continental Machines, Incorporated, Savage,
 Minn., a corporation of Minnesota

Application October 7, 1949, Serial No. 120,107

1 Claim. (Cl. 33—168)

1

My invention relates to improvements in gauge blocks and the method of forming same.

It is well recognized that it is highly undesirable to have any sharp edges present on gauging blocks because of the ease of nicking, denting, or otherwise causing burrs by bringing such sharp edges in contact with other hard material. Such burrs or dents greatly impair the utility of the blocks. Therefore, it is now common practice to join the gauging faces with the perpendicular non-gauging faces or marginal connecting sides by arcuate or bevelled surfaces. This has, to a large extent, eliminated sharp edges and greatly reduced the tendency of the blocks to become burred or nicked. However, even rounding the corners between the gauging faces and the marginal connecting sides has not proved entirely satisfactory for the reason that said rounding must be done prior to final lapping to size and polishing of the gauging faces. Such lapping to size necessarily removes some of the amorphous metal, which necessarily reduces the block somewhat in thickness. Therefore, obviously after such lapping, the curved portions connecting the marginal sides with the gauging faces are no longer tangent with said gauging faces—with the result that a small but objectionable edge has been created.

The primary object of my invention is to provide a block wherein the curved surfaces connecting the marginal sides with the gauging faces are such that it is impossible to create any appreciable edge by such lapping and finishing operations.

More specifically, the object of my invention is to provide an arcuate curve extending approximately forty-five degrees from the marginal sides and thereafter connecting said arcuate surfaces with the gauging faces by means of parabolic curves, the portions of said parabolic curves of greatest radii being adjacent the gauging surfaces.

Other objects and advantages of my invention will become apparent from the following detailed specification, appended claim, and attached drawings.

Referring to the drawings:

Fig. 1 is a greatly enlarged fragmentary view in side elevation of a gauge block having the corners between a gauging face and an adjacent marginal face rounded in a conventional manner; and

Fig. 2 is a view corresponding to Fig. 1 but showing a gauge block having said corners formed in accordance with my invention.

2

It is well known that a selected block of steel must undergo a number of machining and normalizing or seasoning operations in order that a finished gauge block is obtained having a high degree of accuracy and freedom from internal strains which might cause minute but critical changes in the dimensions of the finished block.

The blocks are machined to a size somewhat greater than the desired finished size, hardened, so-called "finish" ground to nearly the required thickness, and seasoned by various heat treatments and aging. The corners between the gauging faces and adjacent marginal connecting sides as well as those between adjacent marginal sides, are rounded to eliminate sharp edges. This may be done before or after the seasoning operations, as desired. The final mechanical operation in the manufacture of gauging blocks is the lapping of the gauging faces to the exact block thickness required. In Fig. 1, a portion of a conventional gauge block is shown as having a gauging face 1 and adjacent marginal connecting sides 2 and 3. A semi-finished face 4, shown by dotted lines, is obtained by grinding as above indicated. The corners between the semi-finished gauging faces 4 and adjacent marginal sides are rounded on an arc, said arc being shown between the face 4 and the marginal side 2 and indicated by 5. It will be noted that the arc 5 is tangent at one end to the semi-finished gauging face 4 and at its other end to the marginal side 2. When the gauging face is then lapped to final finish, as at 1, the tangent therebetween and the arc 5 is destroyed and a definite edge or corner 6 is formed. This edge 6, though relatively minute, is objectionable in that it is subject to injury, such as dents, nicks, or burrs, caused by careless handling. Moreover, during the final lapping operation, a certain amount of block material in an amorphous state is pushed out to and beyond the edge 6 where it adheres to the arcuate corner surfaces 5 and forms objectionable burrs. A gauge block produced in accordance with my invention is illustrated in Fig. 2 and comprises a finished gauging face 7, marginal sides 8 and 9, and a cross-sectionally curved corner 10 connecting the gauging face 7 with the marginal side 8. My improved block is built in a manner similar to that described except that the curved corner 10 is formed on an arc 11 for approximately forty-five degrees from the plane of the marginal side 8 and on a parabolic curve 12 for the remaining portion thereof. The arc 11 is tangent at one end with the marginal side 8 and 55 at its other end with the end of the parabolic

curve 12 having the shorter radius, the end thereof having the longer radius being tangent to the gauging face 1.

In producing my improved gauge block, the arc 11 is formed prior to the final finish lapping operation of the gauging surfaces. The semi-finished or ground surface is shown by dotted lines in Fig. 2 and indicated by the numeral 13. This surface is finish-lapped to provide the gauging face 1, after which the corners are buffed to provide the parabolic curves 12. The buffing operation removes any amorphous block material which may have accumulated at the edge portions of the gauging faces and removes the edges formed by the lapping operation. If desired, the parabolic curves may be added to the block before the final finish lapping operation. I have found that this method may be followed with satisfactory results for the reason that any edge formed between the flat gauging face 1 and the adjacent end of the parabolic curve 12 is so minute as to be inconsequential.

I have further found that gauge blocks produced according to my invention have a substantially greater resistance to nicking and burring at the corners between the gauging faces and connecting marginal sides and a correspondingly longer useful life than conventional gauge blocks.

While I have shown and described a commercial embodiment of my improved gauge block and the method of producing the same, it will be understood that the same are capable of modification without departure from the spirit and scope of the invention as defined in the appended claim.

What I claim is:

A gauge block including a body member hav-

ing opposed parallel flat gauging faces, side walls intermediate the gauging faces and in normal relation thereto, and curved surfaces between the side walls and the margins of said gauging faces, the curved surfaces as observed in a cross section of the block each including a circular arcuate portion of substantially 45° extent extending from a side wall in tangent relation thereto and an arcuate portion extending uninterruptedly from the first arcuate portion to the margin of the corresponding gauging face, the second arcuate portion being of substantially greater linear extent than the first arcuate portion and being of increasingly greater radii from the first arcuate portion to the margin of the gauging face, whereby a relatively wide curved surface is provided between the margin of each gauging face and the side walls and the surface defined by said second arcuate portion defines relatively small angles with said gauging face and planes parallel therewith to avoid burr producing impacts with other blocks movable parallel with said gauging face.
